INSECTICIDE SPRAYER OR THE LIKE

James G. Sawyer, Snyder, N.Y., assignor to General
Turbine Corp., Buffalo, N.Y.

Filed May 4, 1962, Ser. No. 69,981

Term of patent 14 years

(Cl. D31—3)

FIG. 1

FIG. 2

FIG. 4

FIG. 5

FIG. 3

FIG. 7

FIG. 6

FIG. 8

FIG. 1 is a front perspective view, showing my new design therefor;

FIG. 2 is a perspective view of the diametrically opposed side of FIG. 1;

FIG. 3 is a side elevational view;

FIG. 4 is a right end elevation of FIG. 3;

FIG. 5 is a top plan of FIG. 3;

FIG. 6 is a rear elevational view;

FIG. 7 is a left end elevation of FIG. 3; and

FIG. 8 is a bottom plan view of FIG. 6.

The dominant features of my design reside in the portions shown in full lines.

I claim:

The ornamental design for an insecticide sprayer or the like, substantially as shown and described.
